UNITED STATES PATENT OFFICE

JOHN RUSSELL TWISS, OF NEW YORK, N. Y.

STOMACH TUBE OR THE LIKE

Application filed April 27, 1932. Serial No. 607,875.

The invention concerns an appliance for drawing fluids from, or introducing the same into the duodenum, stomach, or the like, and relates particularly to the employment in such appliance of a bucket in connection with the conduit tube, and also of a ball or weight connected with the bucket in such manner as to act as a leader, having freedom of movement in various directions relative thereto.

The invention consists in the features, and arrangement and combination of parts hereinafter described and particularly pointed out in the claims.

15 In the drawing:

Figure 1 is a sectional view of the invention in one form.

Fig. 2 is a lengthwise sectional view of the bucket member.

20 Fig. 3 is a transverse sectional view of the bucket member.

Fig. 4 is a view of another form of the invention.

Fig. 5 is a lengthwise section of the bucket member of Fig. 4.

25 Fig. 6 is a transverse sectional view of the bucket member of Fig. 4.

The flexible duodenal tube is shown in part at 1. This is formed of rubber and is of about $\frac{3}{16}$ " in diameter, and approximately four and a half feet long. This tube carries at its end a hollow member 2 generally known as a bucket. It is formed of metal and is intended to provide the means for fur-

30 nishing the proper arrangement of inlet openings to the tube, or in case fluids are to be introduced into the patient these open-

35 ngs form the outlet from the tube. This metal member is provided with end portions

40 or shoulders 3 of slightly larger diameter than the rubber tube which may be attached thereto by a wrapping of silk thread. The

45 rubber tube fits upon a hollow nipple 2a ex-

tending from the end face of this metal tip or bucket. The bucket intermediate of the

45 end portions or shoulders 3 is provided with perforations in the form of slots 4 in its wall

and these are of a length to extend substan-

50 tially from one end portion to the other.

These slots form the inlet openings to the

bucket and hence to the tube when the device is used for evacuation, or, on the contrary, these openings form the outlets from the tube when used for introducing fluids into the patient.

55 There are preferably four of these slots 90° apart. Leading to the ends of certain of these slots are grooves or channels 5 in the shoulders or end portions 3. The disposition of the slots 4 and the channels 5 60 relative to the shoulder or end portions of the bucket is such that a free communication is afforded to and from the tube 2 when the appliance is in operation, because the shoulders or end portions of the bucket will prevent the wall of the stomach or duodenum when in collapsed condition from closing these slots and channels by affording stops or bearing surfaces for the said collapsed wall, thus acting to hold it off from the slots 65 and channels sufficiently to maintain them in open condition. Preferably the intermediate part of the bucket is of considerably reduced diameter in respect to the end portions or shoulders, and the slots are formed 70 in this reduced portion, and the channels 5 lead to these slots. Furthermore this reduced intermediate portion of the bucket 75 may be of generally concaved formation, its smallest diameter being about midway of 80 its length, and gradually increasing in diameter towards the end portions or shoulders, though the invention is not limited in this respect.

This concave formation avoids the existence of abrupt shoulders or edges on the bucket. Beyond this terminal tip or bucket is located a weight or leader member 6.

This may be of various forms, for instance, ovoid or globular. In the particular form 85 shown it is of spherical shape. It is spaced apart from the bucket a considerable distance, say two inches, and is connected to the bucket by means which will allow the

90 ball or weight to have in large degree free-

95 dom of movement, independently of the bucket both laterally in respect to the axis of the bucket and flexible tube, and also

about its own axis, or in other words, about 100 that pole which is attached to the bucket.

The means for attaching this ball or weight to the bucket may assume various forms, but in each form it is desirable that the freedom of movement of the ball relative to the 5 bucket and main tube be provided for. In Fig. 1 this connection is shown as rubber tubing 7. This tube is more highly flexible than the rubber conduit tube. It lends itself to convenient attachment both to the 10 ball and to the bucket, each of said parts having a projection marked respectively 8 and 9, over which the rubber tube is stretched, and secured by a silk thread. The diameter of these projections is somewhat 15 less than the adjacent parts of the bucket, and ball respectively, and in respect to the ball or weight the connection is such that the working surface of the ball is available at all points excepting the comparatively small 20 area covered by the attached end of the rubber tube connection, and the stud surrounded thereby, it being noted that the ball is of larger diameter than the joint between said ball and the connecting tube.

25 The silk thread windings are held without knotting said thread. This may be done by carrying the end of the thread under the wrapped strand or strands, so as to be held clamped in position thereby.

30 In Fig. 4 is shown a slightly different form of bucket. The main difference between it and the form described above is that the intermediate slotted part is not concaved. The slots and channels above described are 35 present in this form also and are so disposed that any collapsing of the wall of the stomach or duodenum will not act as a closure and create vacuum. The slots in this form are marked 4a and the channels leading 40 thereto are marked 5a.

In this form the connection between the leading weight or ball is shown as a flexible member, for example a chain 10 covered by a tubular rubber sheath 7a. The chain is 45 attached to a swivel pin 10' having a head 11 bearing on a washer 12 within the hollow bucket, the said pin being adapted to turn about its axis to accommodate any rolling action that the ball may tend to have. In 50 this swivelling action the movement will take place relative to the bucket which, therefore, will be relieved in large measure of tendency to turn about its axis and twist the main conduit tube 1. The flexible connecting member or chain is attached to the ball by a pin 13 screw threaded into the latter. The covering tube 7a of rubber, which is intended to protect the chain, and also to avoid contact of said chain with the wall of 60 the cavity in which the device operates, may be made of highly flexible rubber tubing fastened to the pin 13 by a silk thread wrapping. At its other end this rubber sheath is attached by a silk thread wrapping to a 65 collar 14 which is mounted rotatively upon

the swivel pin 10'. By these swivel members 10 and 14 the leader ball or weight may have rotative movement about its own axis without affecting the bucket or the conduit tube, and by reason of the highly flexible character of the chain and the thin rubber sheathing enclosing the same, the ball may have freedom of movement in various directions relative to the bucket.

70 The ball in this form of the appliance, like that first described, presents its rounded surface at front, rear and sides for contact with the wall of the cavity in which it operates, it being noted that the diameter of the ball is considerably greater than that of the flexible connection, so that all sides of the ball are exposed, as just stated, in large degree.

75 In use, the rounded terminal mass or ball 6 is inserted into the mouth of the patient followed by the bucket and the attached long, narrow, flexible, conduit tube, by means of which the bucket and mass below it are propelled through the esophagus and stomach to the distal end of the stomach known as the pylorus. Here, the rounded terminal mass 80 becomes engaged in the pyloric orifice and is drawn downward by the peristaltic action of the duodenum, assisted by gravity. The terminal mass draws the bucket after it until the bucket reaches the approximate location 85 of the opening of the pancreatic and common bile ducts into the duodenum, its arrival at this point being indicated by the appearance of bile at the upper end of the tube. The upper end of the tube is then held in place 90 by the hand, or by some external temporary attachment, during which time the bucket is also maintained in its position by traction from below, exerted by the rounded terminal mass and its flexible coupling, which is held 95 in place by gravity or aborad peristaltic intestinal action, or both.

100 The bucket may remain in this position as long as necessary. The contents of the duodenum may be drained out by gentle suction or siphonage. Fluids may be injected by means of a syringe for the purpose of stimulating the flow of bile and pancreatic secretions, after which the secretions and stimulating fluids may be drained out. Fluids may 105 also be introduced, with the bucket in this position, for the purpose of lavage, nutrition, or for specific medicinal purposes. After completion of the desired procedure, the bucket is withdrawn by exerting gentle traction on the part of the long narrow tube outside the mouth.

110 An advantage of this improved type of appliance is that it is composed of two units, a small, light, metal bucket and a rounded or ovoid terminal mass in which the weight of the unit is localized. This arrangement 115 allows great ease of entrance into the duodenum and provides assurance of keeping the bucket in position following the use of stimu- 120

lating fluids, because of the following features:

The terminal rounded mass at the end of a flexible coupling is introduced through the 5 pyloric orifice of the stomach and will easily engage in this opening, because a minimal diameter of the mass is always presented, regardless of the angle of approach of the tube.

- 10 The terminal rounded mass is highly mobile, easily seized upon and propelled through the stomach and duodenum towards its destination at the opening of the bile and pancreatic ducts by the peristaltic waves of 15 the stomach and duodenum. This action is aided by the long, light, and flexible character of the connecting coupling, which is of a lesser diameter than that of the terminal mass.
- 20 The metal bucket, being light in weight, short, and of small diameter, is easily drawn after the rounded mass, carrying with it the attached tube, to the duodenum, where the secretions of the pancreas and biliary tract 25 are obtained.

The metal bucket collecting these secretions is retained at the proper place by holding the long, narrow, flexible tube externally, which prevents the further progress of the 30 bucket, and by the traction exerted by the rounded mass or weight and its elongated, flexible coupling, which prevents the regurgitation of the tube from the duodenum back into the stomach.

35 It will be seen from the above that the feature of separating the light, metal bucket from the mass weight of the tip, is an important one, as well as the feature of connecting these parts by a highly flexible connection 40 allowing for substantially complete freedom of the weight to assume different positions.

Further advantages are found in the construction of the metal bucket itself. The shoulders make the total diameter of the 45 bucket at its ends slightly larger than that of the long flexible rubber tube or the diameter of the elongated flexible coupling with the terminal mass. This difference in diameter is not enough to impede the progress of 50 the bucket in either direction in the gastrointestinal canal; it is, however, sufficient to prevent the walls of the stomach or duodenum from collapsing down upon the four 55 slots in the bucket. This collapsing would make impossible the flow of fluids through the slots into the long, flexible tubing and create a vacuum which would prevent movement of the bucket. These shoulders or enlargements constitute guards to protect the 60 slots against closure.

The grooves in the shoulders provide for the free in-flow and outflow of fluids from above or below the bucket through the slots, 65 into or out from the long, flexible tube, re-

gardless of how constricting the surrounding intestinal wall may be.

A further advantage of these grooves is that they prevent the formation of a vacuum between the two shoulders, in cases of a constricted intestinal wall, with the subsequent necessary immobility of the bucket.

An advantage in the construction of the slots is that they are long enough, and have a width almost as great as the lumen of the long, flexible tube, tending to prevent the obstruction of the tube by mucous or débris and allowing any one slot to maintain the entire and adequate flow which is the maximum capacity of the long flexible tube.

The location of these slots in a depression of the bucket, as before stated, relieves the slot of the possibility of complete obstruction by collapse or constriction of the intestinal wall.

The coupling connection for the ball consisting of a thin, narrow, flexible member of greater flexibility than that of the long, flexible tube extending to the mouth, is an advantage in the adaptation of the terminal mass to irregular or rounded surfaces and to the opening of the pyloric orifice.

Except as may be interpreted from the appended claims, the scope of the invention is not limited to the forms or characteristics of the elements described and shown herein, certain of the features being susceptible to modification without departing from the spirit of the invention.

It will be understood that where parts in one form can be used in the other form, they are to be regarded as existing in said other form. Thus the swivel connection in Fig. 4 may be substituted for the coupling member shown in Fig. 1 for holding the ball weight.

I claim:

1. An appliance of the class described, comprising a flexible conduit tube and an attached bucket member, provided with an opening in its wall, and with means at opposite ends of the opening to guard said opening against closure from the wall of the cavity in which the bucket is located.

2. In an appliance of the class described, a flexible conduit tube, a bucket member attached thereto having an opening through its wall and an enlarged portion at each side of said opening to guard the same against closure from the collapsed wall of the cavity in which the bucket is located.

3. An appliance of the class described, comprising a flexible conduit tube and an attached bucket member provided with an opening in its wall, and with means to guard said opening against closure from the wall of the cavity in which the bucket is located, said guard means having a channel or space leading to the said opening, to prevent said opening from being placed out of service.

4. An appliance of the class described com-

- prising a flexible conduit tube and a bucket member attached thereto, having an opening through its side wall for the passage of fluid, said opening being formed in a depressed 5 portion of the bucket wall intermediate the ends of said bucket, which ends provide bearings to prevent closure of said opening by a collapsed wall of the cavity in which said bucket is located.
- 10 5. An appliance of the class described comprising a flexible conduit tube and a bucket member attached thereto having an opening in its wall for the passage of fluid, said opening being depressed in relation to the end portions 15 of the bucket, whereby said ends guard the opening against closure from a collapsed wall of the cavity in which the bucket is located.
- 20 6. An appliance of the class described, comprising a flexible conduit tube and a bucket attached thereto, said bucket having its wall intermediate its relatively larger end portions depressed relative to said end portions and perforated, and a channel extending 25 through said relatively larger end portions and communicating with the perforation for the passage of fluid between said channel and the interior of the bucket and conduit tube, said channel opening to the outside of the 30 bucket and guarded by the end portion against closure by a collapsed wall of the cavity in which the bucket is located.
- 35 7. An appliance according to claim 6 in which the slot and channel extend longitudinally of the bucket.
- 40 8. An appliance of the class described comprising a flexible conduit tube, and a bucket attached thereto, substantially circular in cross section and concaved on its exterior 45 lengthwise with a slot intermediate its end portions, and with a channel through the end portion connecting with the slot and communicating with the outside to prevent closure of communication through the slot to the interior of the bucket and the tube, substantially as described.
- 50 9. An appliance of the class described comprising a flexible conduit tube with a passage associated therewith for the flow of fluid to or from the outside of said tube at or near one 55 end thereof, and a leader weight member spaced apart from that end of said tube with which said passage is associated, and a flexible connection between said weight member and the said end portion of said tube, substantially as described.
- 60 10. An appliance according to claim 9 in which said weight member is rounded on its outer surface.
- 65 11. An appliance according to claim 9 in which the leader weight is of larger transverse dimension than the thickness of the flexible connection.
12. An appliance according to claim 9 in 65 which the leader weight is substantially in the form of a ball, substantially as described.
13. An appliance according to claim 9 in which the flexible connection allows the weight member to have movement about its axis.
14. An appliance according to claim 9 in which the flexible connection includes a swivel joint for allowing the weight member to turn about its axis.
15. An appliance according to claim 9 in which the flexible connection has a swivel joint between itself and the tubular conduit.
16. An appliance of the class described comprising a flexible conduit tube, a bucket of rigid material connected with said tube and having an opening in its wall for the passage of fluid, and a leader weight of rigid material spaced apart from the bucket, and a flexible connection between said rigid bucket and rigid weight, substantially as described.
17. An appliance of the class described, comprising a flexible conduit tube, and an attached bucket member having an opening in its wall, said bucket member being provided with wall portions in outstanding relation in respect to said opening to guard it against closure by the wall of the cavity in which the bucket is located.
18. An appliance of the class described comprising a bucket member having an end wall provided with a projection for the attachment of a flexible member, the end wall being of greater diameter than the flexible member to be attached to the projection, said end wall at one side of the projection having an opening communicating with the interior of the bucket.
19. An appliance of the class described, comprising a flexible conduit tube and an attached bucket member having an opening in its wall to one side of the flexible conduit tube and a second opening in its end communicating with the first named opening to prevent complete closure of the first named opening in the event that a portion of the wall of the cavity in which the bucket is located overlies the first named opening.
20. An appliance of the class described, comprising a flexible conduit tube and an attached bucket member provided with a lateral opening and with guard means to prevent closure of said opening by the wall of the cavity in which the bucket is located, said guard means having an aperture which opens at the end of the bucket and communicates with said lateral opening to provide access to the lateral opening in the event that a portion of the wall of the cavity in which the bucket is located overlies the lateral opening.
- In testimony whereof, I affix my signature,
- JOHN RUSSELL TWISS.
